UNITED STATES PATENT OFFICE.

LYMAN E. DODGE AND NEIL D. PRESTON, OF ROCHESTER, NEW YORK, ASSIGNEES TO
GENERAL RAILWAY SIGNAL COMPANY, OF GATES, NEW YORK, A CORPORATION OF
NEW YORK.

AUTOMATIC TRAIN-CONTROL SYSTEM.

Application filed September 7, 1916. Serial No. 118,817.

To all whom it may concern:

Be it known that we, LYMAN E. DODGE and NEIL D. PRESTON, citizens of the United States, and residents of the city of Rochester, in the county of Monroe and State of New York, have invented a new and useful Automatic Train-Control System, of which the following is a specification.

This invention relates to systems for automatically controlling the speed of railway trains.

In the type of systems for automatically controlling the speed of railway trains to which this invention more particularly relates an arbitrary quantity, which corresponds to and varies with the actual speed of the train, is established on the train, and this quantity is compared with another like arbitrary quantity which is caused to vary as the train progresses and to assume at each point in the travel of the train a value corresponding to the permissive speed desired at that point, suitable devices being employed to cause an automatic application of the brakes in case the result of this comparison shows that the actual speed of the train exceeds the desired permissive speed.

In one physical embodiment of this type of system, the arbitrary quantity corresponding to the actual speed is indicated or established by the position of a movable member or part which is caused to assume different positions by a suitable speed responsive device, and the arbitrary quantity corresponding to permissive speed is indicated or established by a cam operatively connected to the wheels of the train and moved in accordance with the distance traveled by the train after passing a predetermined reference point in the rear. In applying this system to practical railroad operating conditions the principles and practices of the well known block signaling system are in general adopted, that is, the railroad is divided into space-units, called blocks, and the system is so constructed and arranged as to provide for the proper control of the speed of trains in each of these blocks according to whether or not the next block in advance is occupied by another train, and also according to the fixed hazards or other conditions associated with that block which require limited speeds throughout certain portions of said block. In this adaptation

of the system the reference point at which the cam is set into operation is the entrance end of each block. It is a well known fact to those skilled in the art of railway signaling that the different blocks for a practical railroad are in practice of different lengths, and further that the fixed hazards requiring limitations of speed are different in different blocks and are located at different points in these blocks, so that in applying this system to practical railroad conditions it is necessary to make allowance for the variations in the length of block and for the variations in the position and character of the fixed hazards. Heretofore it has been proposed to make this allowance for the variations in the lengths of blocks by shifting the cam used for establishing permissive speeds so as to change its initial position, and to select the shifted position of the cam desired by selecting mechanism comprising in general certain devices carried by the train which cooperate with other devices located along the track. The large number of different positions of the cam which may be required, however, usually necessitates a large number of selections, and this in turn requires a complicated selecting mechanism capable of giving this large number of selections. With these considerations in mind, the primary object of this invention is to devise an arrangement and construction of parts such that the shifting of the cam used for establishing permissive speeds to any desired position may be obtained by causing the cam to be moved at different desired points in the travel of the train in proportion to a predetermined distance traveled by the train at these points.

Other objects and advantages will appear as the description of the invention progresses, and the novel features of the invention will be particularly pointed out in the appended claims.

In describing the invention in detail reference is had to the accompanying drawings, wherein we have illustrated a preferred physical embodiment of our invention, and wherein like characters of reference designate corresponding parts throughout the several views, and in which:

Figure 1 is a diagrammatic view showing in a simplified form one physical embodiment of the parts of the system embodying

this invention which are carried by the train or vehicle; Figs. 2, 3 and 4 are diagrammatic views of portions of a railroad track which illustrate some of the conditions which the system embodying this invention is capable of satisfying and which show an arrangement of trackway circuits capable of controlling the mechanism illustrated in Fig. 1 to obtain the desired results, the permissive speeds at the different points along these portions of track being illustrated according to the well known method of plotting curves; and Figs. 5 and 6 illustrate modified forms of devices for controlling the mechanism shown in Fig. 1.

Referring to the accompanying drawing, particularly to Fig. 1, the numerals 1 and 2 designate portions of the track rails of an ordinary railroad track; and the numerals 3 and 4 designate a pair of wheels of a railway train or vehicle, these wheels being connected by the usual axle 5. According to the particular embodiment of the invention illustrated, the impulse for controlling the mechanism on the train is transmitted from the track to the train by means of a contact shoe and ramps, and in Fig. 1 this contact shoe is shown in a simplified form as comprising a plunger 6 mounted in a bracket 7 so as to move vertically, said plunger 6 being urged to its lower position by a spring 8. To the upper end of the plunger 6 is fixed a button 9 of suitable insulating material which is adapted to engage the upper face of the bracket 7 and limit the downward movement of said plunger. Carried by the bracket 7, which for simplicity is assumed to be made of insulating material, is a contact spring 10 and a contact piece 11, which are normally in contact with each other and which are so arranged and constructed that when the plunger 6 is raised the contact spring 10 is separated from the contact piece 11.

Secured to the axle 5 is a beveled gear 12 which meshes with a beveled pinion 13 fixed to a shaft 14. The shaft 14 is arranged to drive a shaft 15 preferably by means of suitable mechanism which operates to drive the shaft 15 in the same direction regardless of the direction of rotation of the shaft 14. In the construction illustrated, this automatic reversing mechanism comprises a beveled gear 16 fixed to the shaft 14 and meshing with two beveled pinions 17 and 18 which are loosely mounted on the shaft 15 and are arranged at diametrically opposite points with reference to the beveled gear 16, suitable collars 19 being secured to the shaft 15 to hold the beveled gears 17 and 18 against endwise movement. Mounted on the shaft 15 between the beveled gears 17 and 18 is a sleeve 20 having a longitudinal slot 21 therein through which passes a pin 22 fixed to the shaft 15. The ends

of the sleeve 20 are provided with clutch teeth 23 facing in opposite directions and the hubs of the beveled gears 17 and 18 are formed with clutch teeth 24 adapted to engage said clutch teeth 23. The operation of the automatic reversing mechanism will be apparent, the sleeve 20 being automatically shifted to connect one or the other of the beveled gears 17 and 18 to the shaft 15 according to the direction of rotation of the beveled gear 16, thereby automatically changing the gear connection between shafts 14 and 15 so as to cause the shaft 15 to always rotate in the same direction. The purpose of this reversing mechanism is to obtain the same direction of rotation of the shaft 15 and its connected parts regardless of the direction in which the vehicle carrying the mechanism is headed.

The speed responsive device G illustrated is of the centrifugal type, similar in construction to the well known centrifugal governor, and comprises a collar 25 fixed to the shaft 15 and a collar 26 loose on the shaft 15. Weights 27 are pivotally connected to links 28 which are pivotally connected to the collars 25 and 26, respectively. The collar 26 is formed with a circumferential groove 30 in which are disposed rollers or pins 31 secured in the bifurcated ends of an arm 32 which is pivotally mounted on a fixed pin 33 and which is rigidly connected to a downwardly extending arm 34, hereinafter termed the speed arm.

To the upper end of the shaft 15 is fixed a beveled gear 35 which meshes with a similar beveled gear 36 fastened to a shaft 37, and also fixed to the shaft 37 is a worm 38 which meshes with a worm wheel 39 fixed to a shaft 40. Arranged substantially parallel with the shaft 40 is another shaft 41, hereinafter termed the cam-shaft, to which is fixed a cam 42. The shaft 40 is arranged to drive the shaft 41 through two groups of gearing X and Y, the group of gearing X being used to turn the shaft 41 and the cam 42 fixed thereto in accordance with the distance traveled by the train, and the group of gearing Y being used to shift the position of the cam 42. Referring to the group of gearing X, a gear 43 is fixed to the shaft 40, and loosely mounted on the shaft 40 is an arm 44 having an upstanding extension 45. Carried by the arm 44 are two intermeshing gears 46 and 47, the gear 46 being also in mesh with the gear 43. Pivotally connected to the extension 45 is a pawl 48 which is pressed in a counterclockwise direction, as viewed in Fig. 1, by a spring 49 against a stop pin 50. A gear 51 is fixed to the shaft 41 and is arranged in the same plane as the gear 47 and the pawl 48. Below the arm 44 is positioned an electromagnet 52, hereinafter termed the

cam-starter magnet, having an armature 53 which is secured to a rod 54 connected to the arm 44, the rod 54 being urged upward by a compression spring 55 interposed between the yoke of the electromagnet 52 and a collar fixed to said rod 54.

The group of gearing Y comprises a gear 56 secured to the shaft 40 and meshing with a gear 57 secured to a gear 58. The gear 58 drives a gear 59 to which is fixed a gear 60 which drives a gear 61. Mounted to turn about the same axis as the gear 61 is an arm 62 which carries two intermeshing gears 63 and 64, the gear 64 being also in mesh with the gear 61. The arm 62 is moved by an electromagnet 65, herein-after termed the selecting magnet, in substantially the same way as the arm 54 is moved, the electromagnet 65 having an armature 66 secured to a rod 67 which is connected to the arm 62 and which is urged to the position shown in Fig. 1 by a compression spring 68. Arranged in the same plane with the gear 63 is a gear 69 which is loosely mounted on the shaft 41, and this gear 69 is provided with a counterweight 70 which tends to rotate said gear in a clockwise direction as viewed in Fig. 1, to the point where a stop 71 carried by said gear strikes a fixed stop 72. The gear 69 is provided with an integral lug or projection 73 which is arranged to strike an arm 74 loosely mounted on the shaft 41. Encircling the shaft 41 is a spring 75, one end of which is fixed to the arm 74 and the other end of which is fixed to said shaft 41; and fixed to the arm 74 is a pin 76 which is adapted to engage a pin 77 fixed to the shaft 41 so as to prevent movement of the arm 74 in a clockwise direction, as viewed in Fig. 1, relatively to the shaft 41.

The cam 42 is provided with a counter-weight 78 which is so positioned as to cause the cam 42 to tend to assume the position shown in Fig. 1.

The comparison between the arbitrary quantity corresponding to the actual speed, which is established as a position of the arm 34, with the arbitrary quantity corresponding to the permissive speed which is established by the cam 42, is obtained by an arrangement of parts comprising a floating lever 79 pivotally connected at its lower end to the arm 34 and carrying at its upper end a freely revoluble roller 80 arranged to bear against the edge of the cam 42. Pivotally connected to the middle point of the floating lever 79 is a link 81 which is pivotally connected to an arm 82 of a sector-shaped member 83 mounted for rotation upon a fixed pin 84, the arm 82 being spring pressed in a direction away from the floating lever 79 by a tension spring 85. The curved edge of the sector-shaped member 83 is provided

with two shoulders 86 and 87, the purpose of which will be more fully explained hereinafter. Disposed adjacent to the sector-shaped member 83 is a fixed block 88 of suitable insulating material on which are supported three contact fingers 89, 90 and 91. One of these contact fingers 89 carries a roller 89' which bears against the curved edge of the sector-shaped member 83. The contact fingers 89, 90 and 91 are resilient and are so arranged as to tend to move to the left, as viewed in Fig. 1, and associated with each of these contact fingers is a fixed stop 92 which serves to limit this movement toward the left, these fixed stops 92 for the different contact fingers being so located as to permit the contact finger 89 to move farther to the left than the contact finger 90, and the contact finger 90 to move farther to the left than the contact finger 91, for the purpose more fully explained hereinafter.

It is contemplated according to this invention that the train to which the system is applied will be equipped with some form of automatically operated brakes or other means for retarding its movement, and in the embodiment of the invention illustrated provision is made for operating the well known system of air brakes. This system of air brakes is too well known to require any detailed illustration and description, and since it forms no part of the present invention, only that part thereof has been shown as is necessary to illustrate the manner of control of the brakes by the automatic train control system. This system of air brakes comprises a train pipe 93, and as is well known by those skilled in the art, the venting of this train pipe causes an automatic application of the brakes. In Fig. 1 the means for venting the train pipe is shown as a valve 94 having a stem 95 and provided with a spring 96 tending to move the valve 94 to its open position. The valve 94 is held in its closed position by a solenoid 97, which when energized pulls upward upon the valve stem 95 with sufficient force to overcome the tension of the spring 96.

It is contemplated according to this invention that prior to the automatic application of the brakes a suitable warning signal will be given to the engineer to advise him that it is necessary for him to reduce the speed of his train in order to avoid being automatically stopped. In Fig. 1 this warning signal is shown as a whistle 98 adapted to be operated by air pressure and connected by a pipe 99 to a source of compressed air, as for example, the train pipe 93. The operation of the whistle 98 is controlled by an electrically operated valve designated generally 100, and the arrangement and construction of parts pre-

ferred is that in which the whistle 98 is sounded when the electrically operated valve 100 is deenergized.

Carried by the train is a control relay SC, having armatures 101, 102, 103 and 104 for opening and closing certain circuits hereinafter more fully explained which serve to control the operation of certain parts of the mechanism carried by the train. Also carried by the train is a pick-up relay P having a neutral armature 105 and a polarized armature 106.

The electrical connections between the different parts shown in Fig. 1 will not be pointed out in detail since these electrical connections and the different controlling circuits established will be set forth at length in the following description of the operation.

Referring to Fig. 2 in the accompanying drawing, there is illustrated a portion of a railroad track over which the normal direction of traffic is from left to right, as indicated by the arrow T. The track rails 1 and 2 of this portion of track are divided by insulating joints 107 into track circuit blocks, designated A, B, C, D and E, only the entire length of the blocks B, C, D and E being shown.

The length of these blocks has been selected arbitrarily to illustrate certain conditions which may occur in practice, and it is to be understood that the particular arrangement of blocks of the particular relative length illustrated has been merely chosen as an example and that the same conditions may be found in various other combinations. As illustrated, the block B is the longest block, the block D the next longest, the block C the next longest and the block E the shortest, the block E being preferably the shortest block occurring on the railroad equipped with this system. Each of these blocks is provided with the well known normally closed track circuit comprising a track battery 108 and a track relay, the track relays for the blocks B, C, D and E being designated 109, 110, 111, and 112, respectively. These track relays are provided with armatures illustrated according to established convention, and for simplicity these armatures are given the same reference characters as the track relays with the distinctive exponents "1" and "2" added thereto.

Associated with each block and located adjacent to the entrance end thereof is a ramp or contact rail, the ramps for the block B, C and so on being designated RB and RC, and so on. These ramps are of any suitable construction and may be located on either side of the track or between the track rails, and are supported in any suitable way but insulated from the track rails so that the contact shoe or plunger 6 (see Fig. 1) will make electrical contact with these ramps

and will also be raised vertically by the engagement with these ramps as the train successively passes them. In general, with the particular exception of the shortest block E, the ramp at the entrance to each block is divided in any suitable manner into sections insulated from each other, for instance, the ramp RB adjacent to the entrance end of the block B is divided into two sections RB and RB¹ insulated from each other, the line of division or insulation being shown conventionally and being approximately opposite to the adjacent insulating joint 107. Associated with these sections of ramps, as the sections RB and RB¹, are controlling circuits including sources of current which serve to establish a difference of potential between a ramp section and the adjacent track rail. The differences of potential between the ramp sections which may be established not only may vary in intensity but are also of different polarity in the manner and for the purposes hereinafter explained.

Above the portion of the track above mentioned there are shown in Fig. 2 a series of curves which indicate permissive speeds at different points along this portion of track. These curves are drawn in accordance with the well known method of plotting speed and distance curves to rectangular coordinates, and are derived from the braking curves of the kind of equipment used on the railroad. In these curves the horizontal distances represent the distance of travel of the train over the successive blocks to any arbitrary scale which corresponds in scale with that to which the length of the blocks is shown, and the vertical distances represent permissive speeds to an arbitrary scale of speed in miles per hour, or in any other suitable units. The lower horizontal line *a* represents zero speed, and the horizontal line *b* represents some predetermined low speed, such as 5 miles per hour, 8 miles per hour, or some arbitrarily chosen figure which seems best adapted to the particular conditions of the railroad in question. The curves for the different blocks are based on the same principles and a description of one will suffice for all. Referring to the block B, the curve *c* (the curve drawn as a heavy full line) represents for each point in the length of the block B the proper permissive speed for that point when the train should proceed cautiously with a view of coming to a stop or to a predetermined low speed by the time it reaches the end of the block B. This curve *c* is derived from the braking curve for the kind of equipment traveling on the railroad, and generally speaking, indicates a permissive speed for each point in the length of the block B at which a train may be traveling at that point and yet by an application of its brakes may be brought to a stop before the end of the block B is

reached. It can be seen from Fig. 2 that the curve *c* intersects the horizontal line *b*, indicating a predetermined low speed, at a short distance from the end of the block B, and the curve *c* is so drawn in this case because the particular physical embodiment of the invention contemplates that the train will not be brought to a complete stop at the end of each block but to a predetermined 10 low speed. The distance between the point where the curve *c* intersects the line *b* and the end of the block B may be of any length desired and is adopted principally as a factor of safety.

15 The significance of the curve *c* may be better understood by some illustrations; and for example, assume that, while the block C is occupied by another train, a train enters the block B at a speed of approximately 45 20 miles per hour corresponding to the permissive speed indicated by the curve *c* at the entrance to the block B. Under these conditions it can be seen that it is necessary for the brakes to be immediately applied to the 25 train entering the block B in order that this train may be brought down to a predetermined low speed by the time it reaches the end of the block B. Suppose, however, that a train enters the block B at a lower speed 30 of, for instance, 30 miles per hour, and that the block C is occupied by another train; then, under these conditions, it is not necessary for the brakes to be applied immediately to the first-mentioned train and this 35 train may proceed some distance into the block B before it is necessary to have the brakes applied, this distance being readily determined by continuing the horizontal line corresponding to the speed of this train to 40 the point where it intersects the curve *c*.

In some cases, when a train enters the block B, there will be clear track ahead and it is proper for the train to proceed through the block B at as high a speed as consistent 45 with safety, and the safe speed which the train may attain in the block B is indicated in Fig. 2 by the dash line *p*. This safe speed depends in general upon special local conditions, such as curves, dangerous down 50 grades, and like fixed hazards; and furthermore the speed of the train while it is traveling through the block B not only must be limited with regard to the fixed hazards in the block B but must also be controlled with 55 reference to the speed at which the train may enter the block C and yet be stopped by an application of the brakes before reaching the end of the block C. The limitation in speed required by the last-mentioned condition is indicated by the curved portion 60 of the dash line *p* near the exit end of the block B.

65 Figs. 3 and 4 are similar to Fig. 2 and illustrate other conditions which may be met with in practice and which are satisfied

by the system embodying this invention; but since the principles involved in the curves and in the controlling ramps and partial circuits therefor are the same in Figs. 3 and 4 as has already been explained 70 in connection with Fig. 2, it is deemed unnecessary to enter into a detailed explanation of the meaning of the various lines and symbols shown in Figs. 3 and 4.

75 Before taking up in detail the trackway circuits for establishing differences of potential of the different characters between the several ramp sections of the different blocks shown in Figs. 2, 3 and 4, the effect of these differences of potential of different 80 characters upon the operation of the system will be first pointed out. Referring to Fig. 1, a single ramp section R is illustrated as provided with a number of partial circuits by means of which the differences of potential of the different characters necessary for the proper control of the mechanism on the train may be established between this ramp section R and the track rail 2 by the manipulation of a switch 114. With the switch 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 R and the track rail 2 includes only the battery 123, and this electrical condition of the ramp section R is conveniently termed positive low voltage on the ramp section R. When the switch 114 is moved to its uppermost position into contact with the contact button designated 126, the ramp section R is disconnected from all source of current, and this electrical condition is conveniently termed zero voltage on the ramp section R.

Operation.—Referring to Fig. 1, the parts are shown in the positions which they assume when the train is traveling through the shortest block, as the block E, and the next block in advance is not occupied by another train. In other words, the parts of the mechanism carried by the train are shown in Fig. 1 in the positions which they assume when this mechanism is set for the shortest block and when traffic conditions are such that the train may proceed through that block without regard to any other train ahead. With the parts in this position the control relay SC is normally energized by a circuit which may be traced as follows: Commencing at the battery 127, conductors 128 and 129, relay SC, conductors 130 and 131, armature 101 in its upper position, conductor 132, contact piece 11, contact spring 10, and conductors 133, 134 and 135 back to the battery 127.

When the control relay SC is energized a signal indicating proceed is displayed in the engineer's cab, this signal being shown as a green lamp G which is supplied with current by a circuit which may be traced as follows: Commencing at the battery 127, conductors 128 and 136, armature 102 of the relay SC in its upper position, conductor 137, lamp G, and conductors 138, 139, 140 and 135 back to the battery 127.

Also, when the control relay SC is energized, the cam-starter magnet 52 is supplied with current flowing along a circuit which may be traced as follows: Commencing at the battery 127, conductors 128, 136 and 141, armature 103 of the relay SC in its upper position, conductor 142, windings of the cam-starter magnet 52, and conductors 143, 134 and 135 back to the battery 127. When the parts are in a position shown in Fig. 1 there is imposed a limitation upon the maximum speed which the train may attain at any time, this maximum permissive speed being determined by the existing position of the cam 42. As indicated hereinbefore, the function of the cam 42 is to establish an arbitrary quantity which may be caused to assume different values and to vary according to the different values of different permissive speeds desired. In the particular construction of the cam shown the lengths of the radii of the cam are proportional according to some arbitrary selected scale to the different permissive speeds desired, and the

angular space between the radii is made proportional, according to some arbitrary selected scale, to distance. To illustrate, suppose that when the cam is in the position shown in Fig. 1 the length of the radius of the cam to the point where the roller 80 bears against the edge of said cam represents according to the arbitrary scale chosen a speed of 25 miles per hour, then, as the cam is rotated in a clockwise direction through 75 an angle, for instance, of 5 degrees, which it is assumed is equivalent to a distance of 50 feet, the radius of the cam at this point 5 degrees from its position shown in Fig. 1 is made greater according to the arbitrary 80 scale selected so as to establish a lower permissive speed of the value desired at a point 50 feet from the point at which the permissive speed of 25 miles per hour is desired. The radii of the cam 42 increase with respect to a stationary point as the cam turns in a clockwise direction to establish lower permissive speeds because of the particular construction and arrangement of parts by means of which the comparison of permissive speed and actual speed is obtained, but it is apparent that this particular type of cam may take various other forms and accomplish the same result.

Referring to the means used for comparing permissive speed and actual speed, the arm 34 is operated by the speed responsive device or governor G in accordance with the actual speed of the train, and as the speed of the train increases, this arm 100 34 assumes positions more and more to the left of the position shown in Fig. 1, thereby moving the lower end of the floating lever 79 more and more to the left of the position shown in Fig. 1. Suppose that the cam 105 42 remains stationary, then the point where the roller 80 carried by the upper end of the floating lever 79 bears against the edge of said cam remains stationary and the upper end of the floating lever 79 becomes a 110 fixed fulcrum point. Consequently, as the lower end of the floating lever 79 is moved more and more to the left from its position shown in Fig. 1 by the increasing of the actual speed of the train, the link 81 is moved 115 more and more to the left and causes a clockwise turning of the sector-shaped member 83 against the tension of the spring 85. When the sector-shaped member 83 is turned in a clockwise direction far enough 120 to bring the shoulder 86 opposite to the roller 89' carried by the contact finger 89, the contact fingers 89 and 90 are caused to move together by their resiliency toward the left; and since the contact finger 91 is 125 held against movement to the left by its stop 92, the contact fingers 90 and 91 are separated. The separation of the contact fingers 90 and 91 interrupts a normally closed circuit which prevents the sounding 130

of the warning whistle 98, this normally closed circuit being traced as follows: Commencing at the battery 144, conductor 145, contact fingers 90 and 91, conductor 146, electrically operated valve 100 controlling the whistle 98, and conductors 147 and 148 back to the battery 144. If the sector-shaped member 83 is moved still further in the clockwise direction and the notch 87 at its edge is brought opposite to the roller 89, the contact finger 89 may move still further to the left, while the contact finger 90 is held against further movement to the left by its stop 92, so that a normally closed circuit for energizing the solenoid 97 and holding the valve 94 in its closed position is interrupted, said normally closed circuit being traced as follows: Commencing at the battery 144, conductor 145, contact fingers 90 and 89, conductor 149, solenoid 97 and conductors 150 and 148 back to the battery 144.

From the foregoing it can be seen that when the actual speed of the train attains a certain limiting permissive speed which is determined by the length of the radius of the cam which is in line with the roller 80 at that instant, the brakes are automatically applied, and also prior to the automatic application of the brakes there is sounded a warning signal. The warning signal serves to advise the engineer that the speed of his train is nearly as great as the highest speed consistent with safety at the point along the track where his train is located at that instant, and from this the engineer knows that he should take measures to reduce the speed of his train or otherwise an automatic application of the brakes will result. It can also be seen from the foregoing that, as the cam 42 is moved, the permissive speed for the train established by said cam is changed by reason of the fact that the radii of the cam which determine what the permissive speed shall be are changed. According to the particular construction and arrangement of parts illustrated, the cam 42 is moved in a clockwise direction to cause a reduction in the permissive speed, and the arrangement and construction of parts is further such as to enable the cam 42 to be moved in this clockwise direction exactly in correspondence with the distance traveled by the train. This movement of the cam 42 is accomplished by deenergizing the cam-starter magnet 52, thereby permitting the spring 55 to move the arm 44 upward and bring the gear 47 into mesh with the gear 51, so that the cam shaft 41 is directly connected to the wheels of the train and is caused to turn gradually in a clockwise direction as the wheels of the train revolve. The radius of the cam 42 at its toe or point is designed to correspond to the predetermined low per-

missive speed hereinbefore pointed out, and the radii of the cam 42 are designed to decrease in proportion to the increase in the permissive speed in accordance with the braking curve of the train, exemplified by the curve *c* for the block B hereinbefore explained. Hence, the angular distance according to the arbitrary scale selected between the point or toe of the cam and its position when it is first connected to the wheels of the train is equivalent to the length of a block, and it can be seen that the movement of the cam 42 as the train progresses through the block is caused to establish gradually decreasing permissive speeds in accordance with the braking curve of the train. If the cam 42 has the position shown in Fig. 1 when the cam-starter magnet 52 is deenergized and the cam is connected to the wheels of the train, the cam will be turned in a clockwise direction far enough after the train has traveled a certain distance to bring the toe or point of the cam opposite to the roller 80 and compel the speed of the train to be no greater than the predetermined low speed; but if the cam is shifted in a counterclockwise direction to a new position before the cam-starter magnet 52 is deenergized and the cam is connected to the wheels of the train, the train must travel a greater distance before the point or toe of the cam is brought opposite to the roller 80. Consequently, by rotating the cam 42 around its axis to different positions and then connecting the cam to the wheels of the train allowance may be made for the different lengths of blocks. In a similar way, by rotating the cam 42 about its axis to different positions the maximum permissive speed for the train may be altered.

The cam-starter magnet 52 is controlled by the armature 103 of the control relay SC, being energized so as to disconnect the cam-shaft 41 from the wheels of the train when said relay SC is energized and its armature 103 is in its upper position, and being deenergized so as to connect the cam-shaft 41 to the wheels of the train when the relay SC is deenergized and its armature 103 is in its lower position. Consequently, when it is desired to compel a reduction in speed of a train it is necessary to deenergize the control relay SC, and this is accomplished when the contact shoe 6 strikes a ramp section to which zero voltage is applied because, when said contact shoe engages such a ramp section, said shoe is lifted and raises the contact spring 10 out of contact with the contact piece 11 so as to interrupt the circuit hereinbefore traced for normally energizing the control relay SC. The deenergization of the control relay SC causes its armature 101 to drop and open another break in the above mentioned circuit so that, after the

- contact shoe leaves engagement with the ramp and is returned to its lower position by the spring 8, nevertheless this circuit will not be re-established. Also, when the 5 control relay SC is deenergized the circuit hereinbefore traced for lighting the green lamp G is broken and another circuit for lighting a yellow lamp Y to indicate caution is established as follows: Commencing at the battery 127, conductors 128 and 136, armatures 102 in its lower position, conductor 151, yellow lamp Y and conductors 152, 139, 140 and 135 back to the battery 127.
- In this way, whenever a train passes a 15 ramp section to which zero voltage is applied, the control relay SC is deenergized, with the result that the proceed indication in the engineer's cab is changed to a caution indication, the cam-starter magnet 52 is deenergized and the cam-shaft 41 directly connected to the wheels of the train, and another break is established in the control circuit for the relay SC so that this relay must be energized by some other circuit before 20 its normally closed circuit is effective to retain it energized. The control relay SC, after it has once been deenergized, may be reenergized by raising the armature 105 of the pick-up relay P, and this is accomplished 25 by supplying current to the relay P from the sources of current located along the trackway. When the armature 105 of the relay P is raised, the control relay SC is energized by current flowing in a circuit which 30 may be traced as follows: Commencing at the battery 127, conductors 128 and 129, relay SC, conductors 130 and 159, armature 105 in its upper position, and conductors 160, 140 and 135 back to the battery 127.
- The construction and arrangement of parts 35 is such that the source of current capable of raising the armature 105 of the relay P must be of high voltage when the relay SC is deenergized at the time. Assume that the switch 114 is either in the position shown in Fig. 1 or in the position in contact with the conductor 121 so that either negative high voltage or positive high voltage is applied to the ramp section R. Then, when the contact shoe 6 strikes the ramp section R, the 40 partial circuit along the track terminating at the track rail 2 and the ramp section R, is connected to a partial circuit on the train including the pick-up relay P so that current 45 may flow from the batteries along the track through the pick-up relay P and raise its armature 105. The complete energizing circuit for the relay P when the switch 114 is in the position shown in Fig. 1 and when 50 the control relay SC is deenergized is as follows: Commencing at the ramp section R, contact shoe 6, conductor 153, preventive resistance 154, conductor 155, relay P, conductor 156 to the wheels and axle of the 55 train, thence to the track rail 2, along conductors 119 and 118, batteries 117 and 116, conductor 115, switch 114, and conductor 113 back to the ramp R.
- The resistance 154 is selected so that sufficient current will flow through the relay P 70 and raise its armature 105 only in case high voltage is applied to the partial circuit on the train. Consequently, if the contact shoe 6 strikes a ramp section R to which only low voltage is applied and if the control relay SC is deenergized, there will not be sufficient current flowing through the preventive resistance 154 and the relay P to raise its armature 75 105. If the control relay SC is energized, however, at the time contact shoe 6 engages a ramp section, as the ramp section R, to which only low voltage is applied, nevertheless sufficient current will flow through the relay P to raise its armature 80 105 by reason of the fact that the armature 104 of the control relay SC is now in its upper position and establishes a low resistance shunt consisting of conductors 157 and 158 around the preventive resistance 154.
- From the foregoing it can be seen that the 85 armatures of the control relay SC may be caused to drop, or if in the lower position may be restored again to their upper position or may not be again restored to their upper position, according to the voltage applied to the ramp section with which the contact shoe 6 engages. The voltage applied to the several ramp sections along the track is determined by the trackway circuits in the manner more fully explained hereinafter.
- If a train passes a ramp section, as the ramp section R, to which voltage of one polarity, herein assumed to be negative voltage, is applied, the polar armature 106 of the relay P is shifted to the right, as viewed in Fig. 1, so as to supply current to the selecting magnet 65 by a circuit which may be traced as follows: Commencing at the battery 161, conductor 162, selecting magnet 65, conductor 163, armature 106 and conductor 164 back to the battery 161.
- The energization of the selecting magnet 65 attracts its armature 66 and moves the rod 67 and the arm 62 to the left, as viewed in Fig. 1, against the tension of the spring 68, so as to bring the gear 63 into mesh with the gear 69. The gear 63 is driven by means of the gears 64, 61, 60, 59, 58, 57 and 56 by the shaft 40 which is connected to the wheels of the train so that, when the gear 63 is in mesh with the gear 69, the gear 69 is turned in a counterclockwise direction as the wheels of the train turn. This counterclockwise movement of the gear 69 causes a corresponding counterclockwise movement of the shaft 41 and the cam 42 by reason of the fact that the projection 73 on the gear 69 bears against the arm 74, and the tension of the spring 75 causes the shaft 41 to follow 90
- 95
- 100
- 105
- 110
- 115
- 120
- 125
- 30

the movement of the arm 74. The pawl 48 does not interfere with this movement of the shaft 41 in the counterclockwise direction, but at the same time it acts to hold the shaft 5 41 against returning under the influence of the counterweight 78 from whatever position it may be moved to. As soon as the contact shoe 6 leaves engagement with the ramp section to which negative voltage is applied, 10 or passes from such a ramp section to another ramp section to which positive voltage is applied, the armature 106 is returned to its neutral position in the first case or to its lefthand position in the second case, thereby 15 interrupting the circuit for the selecting magnet 65. The deenergization of the selecting magnet 65 permits the spring 68 to return the arm 62 to its normal position shown in Fig. 1, whereupon the gear 69 is returned 20 to the normal position shown in Fig. 1 by the action of the counterweight 70; but the pawl 48 by engaging with the teeth of the gear 51 holds the cam-shaft 41 and the cam 42 against return movement.

25 The selecting magnet 65 is energized very shortly after the contact shoe 6 engages a ramp section to which negative voltage is applied and remains energized so long as the contact shoe is in engagement with this 30 ramp section and for a short time after the contact shoe leaves engagement with said ramp section. The short intervals of time above mentioned are due to the time required to move the armature 106 of the relay P and to move the armature 66 of the selecting magnet 65, and the apparatus is preferably so arranged and constructed that the interval of time required to move the gear 63 into mesh with the gear 69 after 35 the contact shoe 6 first engages a ramp section is substantially the same as the time required to move the gear 63 out of mesh with the gear 69 after the contact shoe leaves the ramp section, so that regardless 40 of the speed of the train as it passes said ramp section, providing the train maintains a substantially uniform speed, the movement given to the gear 69 is proportional to the length of said ramp section. In this way the cam 42 may be shifted in a counterclockwise direction to varying extents and held in the shifted position by causing the contact shoe 45 6 to engage a ramp section of the desired length to which negative voltage is applied. 50 For the proper control of the control relay SC by the pickup relay P it is necessary that high voltage should be applied to a ramp section sometimes and low voltage at other times; but it is contemplated according to 55 this invention that the polar armature 106 of the pick-up relay P will respond to either negative high voltage or negative low voltage, and for this purpose, if desired, the polar armature 106 may be operated by a separate relay arranged in parallel with the re-

lay P, but not including in its circuit the preventive resistance 154.

Having described the operation of the mechanism carried by the train and the manner in which it may be caused to control 70 the speed of the train as desired by the electrical conditions and lengths of the ramp sections, it is possible to consider now some of the different conditions likely to occur in practice which may be satisfied by this 75 mechanism. Referring to Fig. 2, one condition is illustrated by the blocks B and C, namely the condition in which a long block having a high maximum permissive speed is followed by a shorter block having a 80 lower permissive speed. Assume that the train equipped with the mechanism shown in Fig. 1 is in the block A and about to enter the block B and further assume that neither the block B nor the block C is occupied by another train. The ramp section RB, under these conditions has negative high voltage applied thereto by a partial circuit which may be traced as follows: 85 Commencing at the ramp section RB, conductor 165, armature 109¹ in its upper position, conductor 166, battery 167, conductors 168 and 169, battery 170 and conductors 171 and 172 to the track rail 2. When the contact shoe 6 carried by the train in question first engages the ramp section RB the selecting magnet 65 is energized, as explained hereinbefore, and commences a counterclockwise movement of the cam-shaft 41 from its initial position shown in Fig. 1. 100 This initial position of the cam-shaft 41 is such that the cam 42 establishes a certain permissive speed as for instance that of approximately 25 miles per hour as indicated by the horizontal dot and dash line designated "datum line." This datum line preferably corresponds to a permissive speed which is the same as the maximum permissive speed for the shortest block on the railroad, as the block E, although such an arrangement is not essential. As explained hereinbefore the counterclockwise movement of the cam-shaft 41 continues so long as the contact shoe remains in engagement 105 with a ramp section to which negative voltage is applied, and furthermore the movement of the cam-shaft 41 is proportional to the length of that ramp section. Consequently, the cam 42 is shifted in the counterclockwise direction through an angle proportional to the length of the ramp section RB. The different and increasing permissive speeds established by the cam 42 during this counterclockwise movement while the train is moving over the space equal to the length 110 of the ramp section RB is represented in Fig. 2 by the heavy dash line d and the permissive speed established by the cam 42 after its movement has been completed is indicated by the heavy dash line p, this latter 115 120 125 130

permissive speed being the maximum permissive speed desired for the block B. The partial circuit associated with the ramp section RB¹ under the conditions assumed, 5 where the block C is not occupied, applies positive low voltage to the ramp section RB¹ and may be traced as follows: Commencing at the ramp section RB¹, conductor 174, armature 110² in its upper position, 10 conductor 175, positive terminal of battery 176 and conductors 177 and 178 to the track rail 2. This positive low voltage on the ramp section RB¹ causes the shifting movement of the cam 42 in a counterclockwise direction to cease, and also serves to keep the 15 control relay SC energized. Consequently, the train may proceed along the block B at any speed less than the predetermined maximum speed, indicated by the line p, established by the cam 42 in a position to which it is now shifted. The above operation of 20 selecting a position of the cam 42 to correspond to the length of the block next to be entered by the train is typical of the different blocks in the railroad, and in discussing the operation of the system for the other blocks illustrated in Figs. 2, 3, 4 it will not be necessary to point out this feature of the operation again in detail.

25 Since the block C is shorter than the block B a train cannot enter the block C at as high a speed as it may enter the block B and be brought to the predetermined low speed by an application of its brakes by the time it reaches the end of the block C, and this is indicated in Fig. 2 by the heavy dash lines p and 200, the line 200 representing a lower maximum permissive speed than the line p. For this reason it is necessary to 30 make provision for automatically compelling a reduction in speed of the train near the end of the block B so that the train may enter the block C at a speed not higher than the permissive speed indicated by the line 35 200. This is accomplished by locating between the ends of the block B a ramp section 180 to which zero voltage is applied, so that when the train passes the ramp section 180 the control relay SC is deenergized, 40 the cam-starter magnet 52 is deenergized and the cam-shaft 41 connected to the wheels of the train, as explained hereinbefore. In this way, the train is compelled to 45 reduce its speed and maintain a speed lower than the curve of permissive speed indicated by the dash line 201. The ramp section 180 is located at such a distance from the end of the block B that the reduction in speed in accordance with the curve 201 will 50 bring the speed of the train to the same as or slightly below the maximum permissive speed for the block C indicated by the line 200.

When the train reaches the ramp section 55 RC to which negative low voltage is ap-

plied, as will be apparent by an inspection of the partial circuit associated with said ramp section, the selecting action is again commenced by reason of the fact that the armature 106 of the relay P is shifted to 70 close the circuit for the selecting magnet 65; but since only low voltage is applied to the ramp section RC, and since the control relay SC is deenergized at this time, the armature 105 of the relay P is not raised. Consequently, while the gear 69 is being turned from its normal position shown in Fig. 1 in the counterclockwise direction and is carrying with it the arm 74, the cam-shaft 41 is 75 being gradually turned in a clockwise direction by reason of the fact that the gears 47 and 51 are in mesh, the spring 75 permitting this relative movement of the cam shaft 41 and the arm 74. In other words, 80 while the mechanism for selecting a predetermined position of the cam 42 is acting the cam 42 is also compelling a further reduction in speed, and this operation of the parts continues until the contact shoe 6 85 passes from the ramp section RC onto the ramp section RC¹.

Since it is assumed that the block C is not occupied, negative high voltage is applied to the ramp section RC¹, the partial circuit 90 for establishing this negative high voltage being readily apparent. Consequently, when contact shoe 6 of the train passes onto the ramp section RC¹, the polar armature 106 is not affected and maintains the selecting magnet 65 energized so as to continue further movement of the cam-shaft 41 in the counterclockwise direction. The neutral armature 105 of the pick-up relay P is raised, however, by this high voltage and causes the energization of the control relay SC and the resulting energization of the cam-starter magnet 52, as hereinbefore explained, so that the arm 44 is lowered to bring the gear 47 95 out of mesh with the gear 51. The extension 45 of the arm 44 is moved at the same time and acts to bring the pawl 48 into engagement with the teeth 51 before the gear 47 entirely moves out of mesh with the gear 51 thereby holding the gear 51 and the cam-shaft 41 in the position which they have at 100 that time. This position of the cam 42 establishes a predetermined maximum speed for the train which is indicated by the short horizontal line 202 in Fig. 2. The arm 74 is 105 at this time in position corresponding to the position of the cam-shaft 41 due to the co-operation of the pins 76 and 77, and the gear 69 has not yet been moved far enough from its initial position to bring the lug 73 thereon against said arm 74, but as the movement of the gear continues and the train reaches a point indicated by the point where the dash line d¹ intersects the short dash line 202, the lug 73 strikes the arm 74 and carries it and the cam-shaft 41 further through 110 115 120 125 130

- a slight angle in a counterclockwise direction until the cam 42 reaches the position to establish a permissive speed suitable for the block C and indicated by the line 200.
- 5 This last-mentioned position of the cam 42 is determined by the length of the ramp sections RC and RC¹, for the reasons hereinbefore explained, and consequently said position of the cam 42 is attained when the 10 contact shoe 6 passes from the ramp section RC¹ onto the ramp section RC².
- If the block D is not occupied at this time, the ramp section RC² has positive low voltage applied thereto, or, if the block D is occupied, said ramp section has zero voltage applied thereto as will be readily apparent from the trackway circuits shown in Fig. 2. In either case the polar armature 106 is moved to interrupt the circuit for energizing 20 the selecting magnet 65, thereby disconnecting the gear 69 from the wheels of the train and permitting it to return to its initial position, the cam-shaft 41 and the cam 42 being held in the position to which they have been moved by the pawl 48. The arrangement described which causes the cam 42 to be moved by the progress of the train to a position for establishing a permissive speed (indicated by the line 202) which is less than 30 the maximum permissive speed for the block C (indicated by the line 200) and then moving the cam back again by the selecting mechanism so as to establish the higher permissive speed (indicated by the line 200) is used with the understanding that the inaccuracies of the mechanism with such an arrangement would be on the side of safety; but it is obvious that such an arrangement is not compulsory and may be modified if desired so that the permissive speed established by moving the cam by the progress of the train from the ramp section 180 to the end of the block C may be the same as 40 the permissive speed established by the cam 45 for the block C.

From the foregoing it can be seen that the speed of a train may be properly controlled in the block B so that the train will not enter the shorter succeeding block C at a speed too high to prevent it being brought to the predetermined low speed within the limits of the block C, and further that a new position of the cam is automatically selected by the length of the ramp sections R² and RC¹ so as to accord with the maximum permissive speed for the block C and its shorter length. In this way provision is made for controlling the speed of the train under proceed conditions in passing through a long 55 block into a shorter block.

Suitable provision must be made by this system, however, so as to properly control the speed of the train in the block B under caution conditions, that is, when the block 60 C is occupied by another train, and also to

select the proper position of the cam to accord with the block C. To obtain a clear understanding of how the system of this invention satisfies this condition, assume that a train equipped with a mechanism shown in Fig. 1 is in the block A and that while the block B is not occupied by a train, the block C is occupied. When the contact shoe 6 of the train in question engages the ramp section RB the mechanism acts to select the position of the cam 42 to accord with the block B in the same way as hereinbefore described; and when the contact shoe 6 passes onto the ramp section RB¹, the cam has been moved to the position desired and is held in that 70 position. Under the conditions assumed, since the block C is occupied, zero voltage is applied to the ramp section RB¹ by reason of the fact that the track relay 110 is deenergized and its armature 110² is in its lower 75 position. Consequently, for the reasons hereinbefore explained, the control relay SC is deenergized, and by the resultant deenergization of the cam-starter magnet 52, the cam-shaft 41 is connected to the wheels of the train, so that as the train progresses through the block B, the permissive speed for the train is continuously reduced in accordance with the curve c with a view of bringing the train to the predetermined low speed by the time it reaches the end of the 80 block B.

As the train progresses through the block B and passes the ramp section 180, no action is produced on the mechanism carried by the train, since the control relay SC is already deenergized. When the train reaches the ramp section RC which is connected to negative low voltage, the polar armature 106 is shifted while the neutral armature 105 is not affected, this result being due to the fact that the control relay SC is deenergized at this time and the preventive resistance 154 is included in the circuit for the relay P so as to prevent the lifting of its armature 105 although not preventing the shifting of the armature 106. Consequently, while the control relay SC and the cam starter magnet 52 are not affected, the selecting magnet 65 is energized, and the driving of the gear 69 to select a position of the cam to accord with the block C commences. The cam-shaft 41 cannot respond to this movement of the gear 69 because said cam-shaft is connected to the wheels, but the spring 75 permits the gear 69 to continue its movement the same as if the cam-shaft were free to move. When the train reaches the ramp section RC¹ the movement of the gear 69 continues, since this ramp section has either negative high or low voltage applied thereto. If the train which was assumed to formerly occupy the block C is still in this block, the ramp section RC¹ has low negative voltage applied thereto, which is not effective to 120 125 130

raise the armature 105 and reenergize the control relay SC. Under normal conditions the engineer will bring his train to a stop at this point before reaching the ramp section RC² and will wait until the train ahead leaves the block C. When the train ahead leaves the block C, the voltage applied to the ramp section RC¹ is changed to negative high voltage and this high voltage causes the armature 105 to be raised so as to reenergize the cam-starter magnet 52 and disconnect the cam-shaft from the wheels of the train. The cam-shaft 41 is now free and rotates in a counter clockwise direction under the influence of the counterweight 78 and the tension of the spring 75 until it corresponds with the position to which the arm 74 has been moved by the gear 69. The train now proceeds, the engineer being advised by the changing of the caution indication in his cab to the proceed indication that the block C next in advance is now clear, and while the contact shoe remains in contact with the ramp section RC¹ the gear 69 is connected to the wheels of the train. When the contact shoe 6 passes onto the ramp section RC² the gear 69 is disconnected from the wheels of the train in the same way as previously described leaving the cam in the new position to accord with the block C.

The electrical condition of the ramp section RC² depends upon whether or not the block D is occupied, low voltage being applied to said ramp section if the block D is not occupied, so that the train may proceed at any speed less than the maximum permissive speed established by the new position of the cam (indicated by the line 200). If the block D is occupied by a train, zero voltage is applied to the ramp section RC² with the result that the control relay SC is deenergized and the connection of the cam-shaft 41 with the wheels of the train produced in the same way as hereinbefore described, so that as the train progresses it must keep its actual speed below its permissive speed indicated by the heavy line c¹.

The blocks C and D have been selected to illustrate the condition where a short block is followed by a longer block. Assuming that the position of the cam to accord with the block C has been properly selected as hereinbefore described and assume that the train in question proceeds through the block C until it reaches the ramp section RD. This ramp section RD has applied thereto either high or low negative voltage, depending on whether or not the block D is occupied by another train. In either case the action upon the mechanism on the train is the same as hereinbefore described and results in the gear 69 being shifted to a position, according to the length of the ramp section RD, so as to establish the maximum permissive speed proper for the block D

(indicated by the line 203). As the contact shoe 6 of the train passes from the ramp section RD onto the ramp section RD¹ the movement of the gear 69 ceases since the voltage applied to said ramp section is either zero voltage or low positive voltage, according to whether or not the next block E in advance is occupied by another train. The presence of a train in either the block D or the block E has the same effect upon a train passing through the block C as the presence of a train in either the block C or the block D has upon the train passing through the block B, which has been explained hereinbefore.

The blocks D and E illustrate a condition analogous to that illustrated by the blocks B and C, namely, the condition where a long block is followed by a short block. The block E is shown as the block having the maximum permissive speed the same as the maximum permissive speed established by the cam 42 in the position shown in Fig. 1, and as explained hereinbefore this permissive speed is indicated by the horizontal line designated "datum line" and is preferably selected with the idea that the block E is the shortest block on the railroad. In view of the discussion in connection with the blocks B and C the manner and the control of the speed of a train in the block B so that its entrance speed into the block E will not be too high need not be further considered in detail, the ramp section 181, to which zero voltage is applied, being placed at the proper point in the block E for the same purpose and with the same effect as the ramp section 180 is placed in the block B. It should be noted, however, that since the position of the cam 42 to accord with the conditions in the block E is the same as the position which the cam 42 does assume under normal conditions, due to the counterweight 78, it is unnecessary to cause any selected movement of the gear 69 at the entrance to the block E, and consequently, a single ramp section RE to which positive voltage is applied is sufficient, whether or not high or low positive voltage is applied to said ramp section being determined by traffic conditions in the block E and the next block in advance in the same way as hereinbefore described in connection with the blocks B and C.

Occasion may sometimes require that a train should be compelled to pass over a short section of a long block at a comparatively low speed, as for instance, where there is a sharp curve or other fixed hazards between the ends of a long block. Such a condition is illustrated by the block G in Fig. 3. The condition illustrated by the block G is assumed to be such that throughout a portion of the length of this block the train should not be allowed to exceed a compara-

tively low speed indicated by the heavy dash line 205. In Fig. 3 the heavy dash line 206 indicates the maximum permissive speed for the block F, and the curve c^4 indicates the 5 limiting permissive speed for the train in the block F under caution conditions. The ramp section RG at the entrance to the block G is arranged to have either negative high or negative low voltage applied thereto according to whether or not the block G is occupied, and this ramp section RG is made of such a length as to result in the cam 42 having a position at the time the train actually enters the block G such as to establish a permissive speed for the train of a magnitude indicated by the line 206. In view of the 10 region of low maximum permissive speed in the block G it is necessary to compel the train after it enters the said block to reduce its speed, and this result is accomplished by placing a ramp section RG¹ at the entrance to the block G to which zero voltage is applied, the effect of this ramp section RG¹ being to set the cam 42 into motion to 15 compel a speed reduction in the same way as hereinbefore described. By the time the train reaches the ramp section 182, the indicated permissive speed of the train is substantially the same as the low premissive speed 205 desired, and consequently, it is unnecessary to 20 to continue the movement of the cam in its clockwise direction, and it is only necessary to disconnect the cam-shaft 41 from the wheels of the train and hold the cam-shaft 25 in the position it then has. This is accomplished by applying positive high voltage to the ramp section 182 which has the effect of raising the armature 105 of the relay P, without effecting the selecting magnet 65, 30 so as to energize the control relay SC and the cam-starter magnet 52. The cam-starter magnet 52 being energized moves the arm 44 downward and brings the gear 47 out of mesh with the gear 51 while the pawl 48 is 35 thrown into engagement with the teeth of the gear 51 at the same time. The train now proceeds under the maximum permissive speed limitation indicated by the line 205 until it reaches the ramp section 183 which 40 is located at such a distance from the end of the block G that the train may be brought to the predetermined low speed before reaching the end of said block. It is apparent from the foregoing discussion that 45 if the block H is occupied by a train it is necessary to set the cam 42 into motion at the point where the ramp section 183 is located so as to compel a reduction in speed of the train according to the curve c^5 . On 50 the other hand, if the block H is not occupied by a train, it is permissible for the train to proceed past the ramp section 183 at any speed less than the permissive speed indicated by the line 205. The control of the 55 mechanism on the train to accomplish either 60 of these desired results is obtained by arranging the trackway circuits, as clearly shown in Fig. 3, so as to apply low positive voltage to the ramp section 183 when the block H is not occupied, and to apply zero 70 voltage to the ramp section 183 when said block H is occupied.

According to the assumed conditions illustrated in Fig. 3 the maximum permissive speed (indicated by the line 207) for the 75 block H is higher than the maximum permissive speed indicated by the line 205, and consequently it is necessary to move the cam 42 to a higher speed position. This is accomplished by the use of ramp sections 80 energized with the necessary value and polarity of current in accordance with the same principles hereinbefore discussed. That is, at the proper point at the necessary distance from the end of the block G the contact shoe 85 6 of the train engages the ramp section RH which has permanently applied thereto low voltage, and this voltage, being negative, commences the selecting movement of the gear 69, without, however, changing the condition of the control relay SC and the cam-starter magnet 52. At the proper point in 90 the block G the ramp section RH¹ is placed and is arranged so that either negative high 95 or negative low voltage will be applied thereto in accordance with traffic conditions in the block H. This voltage applied to the ramp section RH being negative continues the selecting operation of the mechanism, and further serves, by reason of the fact 100 that it is high or low voltage, to reenergize the control relay SC or not reenergize this relay when a train reaches the end of the block G after having been compelled to reduce its speed by reason of the presence of a 105 train in the block H, according to whether or not a second mentioned train is still in the block H or has moved from that block into the next block in advance.

There may be occasions where it is desired 110 to have the maximum permissive speed for a train under proceed conditions throughout the portion of the length of a block near its entrance end less than the length of the block requires, and such a condition is illustrated in Fig. 3 by the block H. In this case it is assumed that the maximum permissive speed desired for a portion of the length of this block at its entrance 115 end is that indicated by the line 207, although the length of the block is such that a train might enter the block H at a higher permissive speed and yet be stopped by its brakes before the end of the block H was reached. To satisfy this condition the cam 42 is moved to a position by the lengths of the ramp sections RH and RH¹ before the train enters the block H so that the shifted position of the cam corresponds to the desired permissive speed indicated by the line 120 125 130

207, and then the cam is held stationary during the travel of the train from the entrance end of the block H until it reaches a ramp section 184. This ramp section 184 is placed at such a distance from the end of the block H that even if the train were traveling as fast as indicated by the line 207, nevertheless by a prompt application of the brakes it could be brought to the pre-determined low speed before reaching the end of the block H. In other words, the location of the ramp section 184 is so chosen that the cam may be set into operation at this point and will act to compel a reduction in the speed of the train according to the curve c^1 , if the presence of a train in the block I next in advance requires such a reduction in speed. The partial circuit for the ramp section 184 is controlled by the track relay 20 of the block I so as to have low positive voltage applied thereto when said block I is not occupied, and also to have zero voltage applied thereto when said block I is occupied. The movement of a train from the block H into the block I is accomplished by the same selecting action and control as hereinbefore described and need not be pointed out in detail.

A still further condition which may be satisfied by the system embodying this invention is illustrated by the block K in Fig. 4. In this case it is assumed that a sharp curve or other fixed hazard makes it necessary to limit the speed of the train throughout the portion of the block K, as between the vertical dot and dash lines 190 and 191 to a comparatively low maximum speed such as indicated for instance by the heavy horizontal dash line 210. And it is further assumed that the part of the block succeeding this portion is of such physical characteristics that a much higher permissive speed is proper, such as indicated for instance by the heavy line 211. In controlling the mechanism on the train to obtain the proper control of the speed of the train and to satisfy these conditions the same principles hereinbefore discussed are carried out. The ramp section RK is made of such length and has negative voltage applied thereto so as to produce the desired shifting of the cam 42; and the ramp section RK¹, to which zero voltage is applied, acts to set the cam into operation from the initial position to which it has been shifted, thereby resulting in the continual reduction in the permissive speed of the train as indicated by the line 209. When the train reaches the ramp section 185 further speed reduction ceases by reason of the fact that this ramp section has high positive voltage permanently applied thereto. The cam 42 is then held stationary throughout the portion of the block K where the restricted speed is desired, whereupon the contact shoe engages the ramp section 186 to which negative low voltage is applied. The length of this ramp section 186 is such as to cause a shifting of the cam 42 to a higher permissive speed position desired and indicated by the line 211. The ramp section 187 is located at such a distance from the end of the block K as will permit the cam to be set into operation if necessary at the ramp section 187 and cause the cam to indicate decreasing permissive speeds as indicated by the curve c^1 . At the end of the block K the proper selection of the cam to accord with the next block in advance and the proper control of the control relay SC in accordance with traffic conditions in said next block in advance is obtained in the same way as hereinbefore described and need not be further discussed.

In the embodiment of the invention previously described and explained the distinction between the ramp section which should perform the function of selecting the position of the cam and the ramp section which should perform the function of controlling the speed control apparatus, is determined by arranging to have either positive or negative current supplied by these ramp sections to the mechanism on the train, the device for controlling the position of the cam being responsive to current of one polarity but not to current of the other polarity. The distinction between the portions of the ramp which should act to cause a shifting of the cam or which should perform only the function of controlling the speed control apparatus may be attained in other ways, however, and one modified arrangement is illustrated in Fig. 5. In this modified construction shown in Fig. 5, the portion of the ramp R¹ which it is desired to have act to cause the cam to be shifted is made to move the contact shoe to a higher position than the other portion of the ramp which performs the function of controlling the speed control apparatus. In this modification the contact shoe is illustrated as an angle lever 192 pivotally connected to the bracket 7, and this angle lever operates a rod 193 to which are fixed but insulated therefrom two contact pieces 194 and 195. The contact piece 194 corresponds to the contact spring 10 and the contact piece 11 in the construction shown in Fig. 1, while the contact piece 195 forms part of an additional circuit controlling device which serves to close a circuit for energizing the selecting magnet 65 when the shoe is raised to its uppermost position, said circuit being traced as follows: Commencing at the battery 127, conductors 128 and 198, selecting magnet 65, conductor 199, contact piece 195 and conductors 189, 134 and 135 back to the battery 127. In other respects the mechanism carried by the train is constructed the same in the modification shown in Fig. 5 as in the arrangement of parts illustrated in Fig. 1, and simi-

lar controlling circuit for the relays SC and P are used as indicated by the corresponding reference characters in Figs. 1 and 5. It is not necessary to divide the ramp R^1 shown in 5 Fig. 5 into separate sections insulated from each other, and the voltage applied to the ramp is either high, low or zero voltage of the same polarity according to traffic conditions for the same reasons and with the same 10 effect as previously described. While the contact shoe 192 is in engagement with the portion of the ramp R^1 between the points designated 196 and 197, which portion is higher than the other portion of the ramp, 15 said contact shoe is raised to its uppermost position and energizes the selecting magnet 65; and it can be seen that the length of the higher section of the ramp R^1 determines the position to which the cam will be shifted. 20 It is also apparent that the contact shoe may be caused to assume different positions in other directions than vertically and produce the same result.

In the modification shown in Fig. 6 the 25 selection of the position of the cam is determined by the length of the ramps located at proper points along the track but on the opposite side of the track from the ramps used to control the speed control apparatus 30 on the train. In this modification there are shown two contact shoes, one on each side of the vehicle, and each contact shoe is also illustrated as an angle lever 220 operating a rod 221 to which two contact pieces 222 and 223 are secured and insulated therefrom. The normally closed circuit for energizing the relay SC includes in series the contact pieces 222 and 222¹ of the contact shoes 220 and 220¹ located on opposite sides of the 35 vehicle; and the contact springs (indicated as arrows in Fig. 6) which cooperate with said contact pieces on the respective shoes are so arranged that when the vehicle is traveling in the normal direction of traffic indicated by the arrow T the contact shoe which is located upon the righthand side of the train at that instant will cause an interruption of the circuit for the relay SC upon engagement with a ramp R^2 located on the 40 righthand side of the track. In case the other contact shoe on the lefthand side of the vehicle traveling in the normal direction of traffic engages a ramp R^3 on the lefthand side of the track the contact piece 222 or 222¹ of this contact shoe will not open the circuit for the relay SC. The normally closed circuit for energizing the relay SC in the modification shown in Fig. 6 may be traced as follows: Commencing at the battery 224, conductor 225, relay SC, conductors 226 and 227, armature 101 of the relay SC in its upper position, conductor 228, contact piece 221¹, conductor 229, contact piece 222 and conductors 230 and 231 back to the 45 battery 234. The conductor 153 connected to one terminal of the winding of the relay P through the resistance 154 and conductor 155 is connected to both contact shoes by the conductors 232 and 233. The circuit for the selecting magnet 65 may be traced as follows: 50 commencing at the battery 234, conductor 235, selecting magnet 65, conductor 236, thence either along conductor 237, contact piece 223¹ and 238 to the conductor 239 and back to the battery 234, or along conductor 240, contact piece 223, conductor 241, to said conductor 239 and back to the battery 234. When the contact shoe, as contact shoe 220¹, on the lefthand side of a vehicle traveling in the normal direction of traffic, engages a lefthand ramp R^3 , the contact piece 223¹ of that shoe is moved into position to close the circuit for the selecting magnet 65; but when a contact shoe, as the contact shoe 220, located on the righthand side of the vehicle engages a righthand ramp R^2 , the contact piece 223 is not moved in position to close the circuit for energizing the selecting magnet 65. In other words, the selecting magnet 65 is energized so long as a lefthand contact shoe on a vehicle is in engagement with a lefthand ramp, but is not affected by the engagement of a righthand contact shoe of the vehicle with a righthand ramp. The lefthand ramps R^3 merely serve the purpose of actuating the lefthand contact shoe and consequently have no voltage applied thereto, whereas the voltage applied to the righthand ramps R^2 is either high, low or zero voltage of either polarity in accordance with traffic conditions in the same way as hereinbefore explained. The arrangement of contact shoes shown in Fig. 6 permits the vehicle to be headed in either direction while traveling in the normal direction of traffic without interfering with the proper operation of the parts, otherwise it would be possible to arrange the contact shoe on one side of the vehicle to control the relay SC and the contact shoe on the other side of the vehicle to control the selecting magnet 65.

It is apparent that various changes may be made in the particular embodiments and modifications of the invention shown in the accompanying drawing and hereinbefore described without departing from the invention; and broadly considered the invention is not restricted to the use of a contact shoe and ramp for obtaining the controlling impulse from the track to the train, nor is it essential that the controlling impulse used for shifting the cam to different positions in accordance with intervals of distance be obtained by the same devices which cause the impulses for controlling the speed control apparatus. Furthermore, while the particular embodiments of the invention shown and described contemplate the shifting of a cam or equivalent device to different positions

to cause variations in the permissive speed for the train, the particular idea of means embodying the invention may be advantageously used to obtain variations in the permissive speed for the train in some other manner.

Although we have particularly described the construction of one physical embodiment of our invention, and explained the operation and principle thereof; nevertheless, we desire to have it understood that the form selected is merely illustrative, but does not exhaust the possible physical embodiments of the idea of means underlying our invention.

What we claim as new and desire to secure by Letters Patent of the United States, is:

1. In an automatic train control system, in combination: a vehicle; a device on the vehicle for establishing permissive speeds therefor; said device being normally held in an initial condition; traffic controlled means for causing said device to change from its initial condition to an ultimate condition under dangerous traffic conditions; and means partly on the vehicle and partly along the track for determining the adjustment of the initial condition of said device at different points in the travel of the vehicle to accord with predetermined intervals of distance traveled by the vehicle at these points.

2. In an automatic train control system, in combination: a vehicle; a device on the vehicle normally in an initial condition and adapted when set into operation to establish gradually decreasing permissive speeds for the vehicle in accordance with its progress along the track; means governed by said device for controlling the speed of the vehicle; traffic controlled means for governing the operation of said device as the vehicle travels; and means partly on the vehicle and partly along the track for determining the adjustment of the initial condition of said device to accord with predetermined intervals of distance at different points in the travel of the vehicle.

3. In an automatic train control system, in combination: a vehicle; speed limiting devices carried by the vehicle and acting to control the speed of the vehicle when its actual speed exceeds a predetermined permissive speed at different points in its travel, said devices having an initial condition and an ultimate condition and adapted when set into operation to be changed gradually from the initial condition to the ultimate condition by the movement of the vehicle; traffic controlled means for governing the operation of said devices; and means partly on the vehicle and partly along the track adapted to determine the adjustment of the initial condition of said devices independently of their change to the ultimate condition to ac-

cord with intervals of distance traveled by the vehicle.

4. In an automatic train control system, a vehicle and a track therefor divided into blocks of different lengths, train control apparatus for the vehicle including a permissive speed device adapted to be changed to an ultimate condition in accordance with the progress of the vehicle along the track, said device being adjustable to accord with the varying lengths of blocks, traffic controlled impulse devices associated with each block for governing the operation of said permissive speed device, and means including said impulse devices for determining the adjustment of said permissive speed device to accord with the length of the corresponding block, said means being effective irrespective of traffic conditions.

5. In an automatic train control system, in combination: a vehicle; a cam carried by the vehicle for establishing permissive speeds therefor; means for causing movement of the cam from its initial position in proportion to the distance traveled by the vehicle; and means partly on the vehicle and partly along the track for changing the initial position of said cam in proportion to intervals of distance at different points in the travel of the vehicle.

6. In an automatic train control system, a vehicle and a track therefor divided into blocks of different lengths, a permissive speed device on the vehicle normally held in an adjusted initial condition and adapted when set into operation to change gradually in accordance with the progress of the vehicle to impose decreasing limitations on the speed of the vehicle, means for setting said device into operation at a control point in each block when the next block in advance is occupied, and impulse transmitting means for adjusting the initial condition of said device at different points along the track irrespective of traffic conditions and in proportion to intervals of distance traveled by the vehicle at such points.

7. In an automatic train control system, a vehicle and a track therefor, automatic train control apparatus for the vehicle including a movable permissive speed device normally stationary in an initial position and adapted to be geared to the wheels of the vehicle under dangerous traffic conditions, control means for governing the movement of said element and its restoration in accordance with traffic conditions, and means comprising elements along the track cooperative with an element on the vehicle for changing the initial position of said element in proportion to intervals of distance traveled by the vehicle at different points along the track.

8. In an automatic train control system, a vehicle and a track therefor divided into blocks of different lengths, an impulse de-

vice at the entrance to each block adapted to transmit two kinds of distinctive impulses to a passing vehicle continuing for a predetermined distance traveled by the vehicle, 5 train control apparatus for the vehicle including an appliance adapted when set into operation to change gradually from an initial condition to an ultimate condition during the progress of said vehicle, said appliance being adjustable to accord with the varying lengths of the blocks, and control means on the vehicle selectively responsive to said distinctive impulses for determining the adjustment of said appliance and for 10 governing its operation.

9. In an automatic train control system, a vehicle and a track therefor divided into blocks of different lengths, an impulse device at the entrance to each block divided 20 into sections each capable of transmitting an impulse of a distinctive character to the passing vehicle, one of said sections being of a length proportional to the length of the corresponding block, train control apparatus for the vehicle including an adjustable permissive speed device, and control means on the vehicle selectively responsive to said impulses of distinctive character for governing the adjustment and operation of said 25 permissive speed device respectively.

10. In an automatic train control system, a vehicle and a track therefor divided into blocks of different lengths, train control apparatus for the vehicle including a permissive speed device adapted when set into operation to change gradually from an initial condition to an ultimate condition, said device being adjustable to vary its initial condition, an impulse device at the entrance to 35 each block controlled in accordance with traffic conditions in the next block in advance for governing the operation of said device, and impulse transmitting means in the rear of each impulse device for adjusting the permissive speed device in proportion to intervals of distance traveled by the vehicle.

11. In an automatic train control system, a vehicle and a track therefor divided into 50 blocks of different lengths, train control apparatus for the vehicle including a permissive speed device adapted when set into operation to establish a predetermined curve of permissive speed, said device being adjustable to vary such curve, impulse transmitting means associated with each block and capable of transmitting to the passing vehicle two distinctive impulses, one dependent on and the other independent of traffic conditions ahead, and control means on the vehicle selectively responsive to said impulses, one controlling the operation of said permissive speed device in accordance 55 with traffic conditions ahead and the other

determining the adjustment of said device 65 to accord with the corresponding block.

12. In an automatic train control system, a vehicle and a track therefor divided into blocks of different lengths, train control apparatus for the vehicle adapted when set 70 into operation to impose gradually decreasing limitations upon the speed of the vehicle and adjustable to vary such limitations, an impulse device at the entrance to each block divided into sections, one section being energized irrespective of traffic conditions and the other section being energized or deenergized in a distinctive manner depending upon traffic conditions ahead, control means on the vehicle selectively responsive to the 75 different energized conditions of said sections of each impulse device for controlling the operation of said apparatus and determining the adjustment thereof respectively.

13. In an automatic train control system, 80 a vehicle and a track therefor divided into blocks of different lengths, train control apparatus on the vehicle including a permissive speed device adapted to be operated to establish decreasing permissive speeds, said apparatus tending to establish a predetermined low permissive speed, means for governing the operation of said permissive speed device in each block with regard to traffic conditions in the next block in advance, and means for causing the permissive speed device to be adjusted to establish higher permissive speeds to accord with the lengths of said blocks, said means comprising 85 an element on the vehicle cooperating with an element along the track and acting to determine adjustments of the permissive speed device which vary in accordance with intervals of distance traveled by the vehicle.

14. In an automatic train control system, 90 a vehicle, automatic train control apparatus on the vehicle including a permissive speed device, means partly on the vehicle and partly along the track for setting said device into operation or restoring it respectively in accordance with traffic conditions ahead, adjustable means for determining the initial condition which said device shall assume when restored, and means comprising 95 cooperating elements on the vehicle and along the track for adjusting said adjustable means to accord with predetermined intervals of distance traveled by the vehicle at control points along the track.

15. In an automatic train control system, 100 a vehicle and a track therefor divided into blocks of different lengths, train control apparatus for the vehicle including a permissive speed device biased to a low speed condition, traffic controlled means for governing the operation of said device at the entrance to each block in accordance with traffic con- 105

ditions ahead, and means for adjusting said device at the entrance to each block to higher speed conditions irrespective of traffic conditions to accord with the length of 5 the corresponding block.

16. In an automatic train control system, a vehicle, train control apparatus for the vehicle including a permissive speed cam biased to a predetermined position, gearing 10 adapted to establish a driving connection between said cam and the wheels of the vehicle to move the same from said predetermined position to higher speed positions, and means automatically controlled from the 15 trackway for alternatively establishing such driving connection or holding the cam against movement from its existing position in response to its bias.

17. In an automatic train control system, 20 a vehicle, train control apparatus for the vehicle including a cam biased to a low speed position, means for adjusting said cam to higher speed positions, gearing adapted to establish a driving connection between the 25 cam and the wheels of the vehicle, and means for alternatively establishing such driving connection or holding said cam against movement to its low speed position in response to its bias.

30 18. In an automatic train control system, a vehicle and a track therefor divided into blocks, a permissive speed device biased to assume a low speed condition, means for adjusting said device to a higher speed condition at the entrance to each block, means 35 adapted when set into operation to cause the permissive speed device to change gradually towards its low speed condition in accordance with the progress of the vehicle, and traffic controlled means for alternatively 40 setting said last mentioned means into operation or holding the permissive speed device in its then existing condition.

19. In an automatic train control system, 45 a vehicle and a track therefor divided into blocks, train control apparatus for the vehicle including a permissive speed cam biased to assume a low speed position, selecting means for adjusting said cam to higher 50 speed positions, gearing adapted to connect the cam to the wheels of the vehicle, control means for alternatively operating said gearing or holding the cam in its then existing position, and impulse devices at the entrance to each block for selectively governing 55 said selecting means and said control means.

20. In an automatic train control system, a vehicle and a track therefor divided into 60 blocks, a permissive speed cam biased to assume a low speed position, means for adjusting said cam to a higher speed position at the entrance to each block, gearing adapted to establish a driving connection

between the cam and the wheels of the vehicle, control means for alternatively establishing such driving connection or holding the cam in its then existing position, and impulse devices at the entrance to each block for selectively governing said control means 65 in accordance with traffic conditions ahead. 70

21. In an automatic train control system, a vehicle and a track therefor divided into blocks, train control apparatus for the vehicle including a permissive speed cam biased to assume a low speed position, selecting means for adjusting said cam to higher speed positions in accordance with intervals of distance traveled by the vehicle, gearing 75 operable to establish a driving connection between the cam and the wheels of the vehicle, control means adapted to alternatively establish said driving connection or hold the cam in its then existing position, and impulse devices at the entrance to each block 80 for controlling said selecting means irrespective of traffic conditions and for governing said control means selectively in accordance with traffic conditions ahead.

22. In an automatic train control system, 85 a vehicle, an automatic train control apparatus therefor adjustable to different initial conditions, selecting means for adjusting said apparatus, said means comprising a movable element, gearing operable to 90 connect said element to the wheels of the vehicle, electromagnetic means and a source of current on the vehicle for governing said gearing, a relay on the vehicle for controlling said electromagnetic means, and impulse devices along the track adapted to 95 control the energization of said relay and to continue such energization for predetermined intervals of distance traveled by the vehicle, said relay and electromagnetic 100 means being adapted to operate in substantially the same time upon energization and deenergization thereof.

23. In an automatic train control system, a vehicle, automatic train control apparatus 110 therefor including a permissive speed cam, means for exerting a tendency to cause said cam to assume an intermediate low speed position, and means adapted to be geared to the wheels of the vehicle and set into 115 operation for predetermined intervals of distance traveled by the vehicle at control points along the track for determining the adjustment of said cam to higher speed positions.

24. In an automatic train control system, a vehicle, automatic train control apparatus therefor including a permissive speed device biased to a low speed condition and adjustable to higher speed conditions, traffic controlled means for governing the operation 125 of said device in each block in accordance with traffic conditions ahead, and means

- adapted to be geared to the wheels of the vehicle and set into operation for a predetermined interval of distance traveled by the vehicle at the entrance to each block for determining the adjustment of said permissible speed device to higher speed conditions.
25. In an automatic train control system, a vehicle and a track therefor divided into blocks provided with normally closed track 10 circuits, an impulse transmitting device at the entrance to each block comprising separate sections, and trackway circuits and sources of current of different electrical characteristics for separately energizing the sections of each device.
26. In a speed control system for railway vehicles, a track, a vehicle thereon, a permissible speed device on the vehicle adapted to be set in a maximum speed position, a 20 minimum speed position and a plurality of sub-maximum speed positions, a single contact shoe carried by the vehicle, intermittent means along the trackway adapted to cooperate with said contact shoe to actuate the permissible speed device to move it to various positions, and means for moving said permissible speed device in accordance with the distance traveled by the vehicle, when said device has been actuated by the 30 means along the trackway to move from a given permissible speed position to a lower permissible speed position.
27. In a speed control system for railway vehicles, a track, a vehicle thereon, a permissible speed device on the vehicle, adapted to be set in a maximum speed position, a minimum speed position, and a plurality of submaximum speed positions, an actual speed device on the vehicle, a single 40 contact shoe carried by the vehicle, intermittent means along the trackway adapted to cooperate with said contact shoe to actuate the permissible speed device to move it to various positions, means for moving said permissible speed device in accordance with the distance traveled by the vehicle, when said device has been actuated by the means along the trackway to move from a given permissible speed position to a lower permissible 50 speed position, means for retarding the vehicle, and means for actuating the retarding means when the actual speed of the vehicle exceeds the permissible speed corresponding to the position of the permissible speed device.
28. In a speed control system for railway vehicles, a track, a vehicle thereon, a permissible speed device on the vehicle adapted to be set in a maximum speed position, a 60 minimum speed position, and a plurality of submaximum speed positions, a single contact shoe carried by the vehicle, intermittent means along the trackway adapted to cooperate with said contact shoe to actuate the permissible speed device to move it to
- various positions, and means on the vehicle for driving said permissible speed device from the wheels of the vehicle, when said device has been actuated by the means along the trackway to move from a given permissible speed position to a lower permissible speed position.
29. In a speed control system for railway vehicles, a track, a vehicle thereon, a permissible speed device on the vehicle, adapted to be set in a maximum speed position, a minimum speed position and a plurality of submaximum speed positions, an actual speed device on the vehicle, a single contact shoe carried by the vehicle, intermittent means along the trackway adapted to cooperate with said contact shoe to actuate the permissible speed device to move it to various positions, means on the vehicle for driving said permissible speed device from the wheels of the vehicle, when said device has been actuated by the means along the trackway to move from a given permissible speed position to a lower permissible speed position, means for retarding the vehicle and means for actuating the retarding means when the actual speed of the vehicle exceeds the permissible speed corresponding to the position of the permissible speed device.
30. In a speed control system for railway vehicles, a track, a vehicle thereon, a permissible speed device on the vehicle, adapted to be set in a maximum speed position, a minimum speed position, and a plurality of submaximum speed positions, a single contact shoe carried by the vehicle, intermittent devices along the trackway adapted to cooperate with said contact shoe to actuate the permissible speed device to move it to various positions, means for moving said permissible speed device, when said device has been actuated by the devices along the trackway to move from a given permissible speed position to a higher permissible speed position, and further means for moving said permissible speed device, when said device has been actuated by the devices along the trackway to move from a given permissible speed position to a lower permissible speed position, said first mentioned means being adapted to move the permissible speed device at a higher rate of speed than said second mentioned means.
31. In a speed control system for railway vehicles, a track, a vehicle thereon, a permissible speed device on the vehicle adapted to be set in a maximum speed position, a minimum speed position, and a plurality of submaximum speed positions, an actual speed device on the vehicle, a single contact shoe carried by the vehicle, intermittent devices along the trackway adapted to cooperate with said contact shoe to actuate the permissible speed device to move it to

- various positions, means for moving said permissible speed device, when said device has been actuated by the devices along the trackway to move from a given permissible speed position to a higher permissible speed position, further means for moving said permissible speed device when said device has been actuated by the devices along the trackway to move from a given permissible speed position to a lower permissible speed position, said first mentioned means being adapted to move the permissible speed device at a higher rate of speed than said second mentioned means, means for retarding the vehicle, and means for actuating the retarding means when the actual speed of the vehicle exceeds the permissible speed corresponding to the position of the permissible speed device.
32. In a speed control system for railway vehicles, a track, a vehicle thereon, a permissible speed device on the vehicle, adapted to be set in a maximum speed position, a minimum speed position, and a plurality of submaximum speed positions, a single contact shoe carried by the vehicle, intermittent means along the trackway adapted to cooperate with said contact shoe to move said permissible speed device in accordance with the distance traveled by the vehicle, when said device has been actuated by the means along the trackway to move from a given permissible speed position to a higher permissible speed position, means on the vehicle for moving said permissible speed device, when said device has been actuated by the means along the trackway to move from a given permissible speed position to a lower permissible speed position, means including said means along the trackway for moving said permissible speed device, when said device has been actuated by the means along the trackway to move from a given permissible speed position to a higher permissible speed position, and means on the vehicle for moving said permissible speed device in accordance with the distance traveled by the vehicle, when said device has been actuated by the means along the trackway to move from a given permissible speed position to a lower permissible speed position.
33. In a speed control system for railway vehicles, a track, a vehicle thereon, a permissible speed device on the vehicle adapted to be set in a maximum speed position, a minimum speed position and a plurality of submaximum speed positions, an actual speed device on the vehicle, a single contact shoe carried by the vehicle, intermittent means along the trackway adapted to cooperate with said contact shoe to actuate the permissible speed device to move it to various positions, means including said means along the trackway for moving said permissible speed device, when said device has been actuated by the means along the trackway to move from a given permissible speed position to a higher permissible speed position, means on the vehicle for moving the said permissible speed device in accordance with the distance traveled by the vehicle, when said device has been actuated by the means along the trackway to move from a given permissible speed position to a lower permissible speed position, means on the vehicle for maintaining the premissible speed device in the position to which it has been moved, means for retarding the vehicle, and means for actuating the retarding means when the actual speed of the vehicle exceeds the permissible speed corresponding to the position of the permissible speed device.
34. In a speed control system for railway vehicles, a track, a vehicle thereon, a permissible speed device on the vehicle adapted to be set in a maximum speed position, a minimum speed position, and a plurality of submaximum speed positions, a single contact shoe carried by the vehicle, intermittent means along the trackway adapted to cooperate with said contact shoe to actuate the permissible speed device to move it to various positions, means including said means along the trackway for moving said permissible speed device, when said device has been actuated by the means along the trackway to move from a given permissible speed position to a higher permissible speed position, means on the vehicle for moving said permissible speed device in accordance with the distance traveled by the vehicle, when said device has been actuated by the means along the trackway to move from a given permissible speed position to a lower permissible speed position and means on the vehicle for maintaining the permissible speed device in the position to which it has been moved.
35. In a speed control system for railway vehicles, a track, a vehicle thereon, a permissible speed device on the vehicle adapted to be set in a maximum speed position, a minimum speed position and a plurality of submaximum speed positions, an actual speed device on the vehicle, a single contact shoe carried by the vehicle, intermittent means along the trackway adapted to cooperate with said contact shoe to actuate the permissible speed device to move it to various positions, means including said means along the trackway for moving said permissible speed device when said device has been actuated by the means along the trackway to move from a given permissible speed position to a higher permissible speed position, means on the vehicle for moving the said permissible speed device in accordance with the distance traveled by the vehicle, when said device has been actuated by the means along the trackway to move from a given permissible speed position to a lower permissible speed position, means on the vehicle for maintaining the premissible speed device in the position to which it has been moved, means for retarding the vehicle, and means for actuating the retarding means when the actual speed of the vehicle exceeds the permissible speed corresponding to the position of the permissible speed device.
36. In a speed control system for railway

- 5 vehicles, a track, a vehicle thereon, a movable member on the vehicle adapted to be set in a plurality of different positions, a permissible speed device on the vehicle
 10 adapted to be set in a plurality of permissible speed positions, each of said positions corresponding to a given position of the movable member, intermittent means along the trackway for moving the movable member
 15 to various positions, means for simultaneously moving the permissible speed device and the movable member, when the movable member is moved in one direction, and means for moving the permissible speed device from one position to another in accordance with the distance traveled by the train, when the movable member is moved in the opposite direction.
37. In a railway traffic controlling system, a railway track divided into blocks, a vehicle thereon, a ramp on said track simultaneously energized by current of different characteristics controlled by said blocks, a device on said vehicle coating with said ramp, and means for indicating the condition of said blocks on said vehicle.
38. Car apparatus for automatic train control systems comprising, a device having an initial condition, means actuated from the trackway and effective to change said device in accordance with the distance traveled by the train while this means is actuated, means for returning said device to its initial condition after each change, a permissive speed device biased to a low speed condition and controllable to assume a higher speed condition corresponding to the changed condition of said first mentioned device, means for maintaining said permissive speed device in such higher speed condition independently of the return of said first mentioned device, and means governed automatically from the trackway for nullifying the effect of said last mentioned means.
39. In an automatic train control system, a vehicle and a track therefor divided into blocks, a permissive speed device on the vehicle adapted to establish various predetermined permissive speeds, means for retarding the movement of the vehicle when the speed thereof exceeds such permissive speed, an influence transmitting device in each block extending a certain distance along the track, and influence receiving means on the vehicle for adjusting said permissive speed device in accordance with the distance traveled while affected by the influence transmitting device and maintaining such adjustment to enforce a continuing predetermined speed limit.
40. In an automatic train control system, a vehicle and a track therefor divided into blocks, of a device on the vehicle having an initial position, an influence transmitting device along the trackway effective for a predetermined distance, means on the vehicle adapted to be actuated by the influence transmitting device for changing the position of said first mentioned device in accordance with the distance traveled by the vehicle while the vehicle carried device is actuated, means for returning said first mentioned device to its initial position, a biased permissive speed device, means for changing the position of said permissive speed device to correspond to the changed position of said first mentioned device, a ratchet device for preventing the return of said permissive speed device, and means governed from the trackway for actuating said ratchet device to its ineffective condition.
41. In an automatic train control system, automatic brake control apparatus on a railway vehicle including changeable permissive speed means and actual speed means cooperating to apply the brakes of the vehicle automatically whenever its actual existing speed exceeds that prescribed by the existing condition of the permissive speed means, adjusting means partly on the vehicle and partly on the track for varying the initial maximum speed condition of said permissive speed means independently of traffic conditions to correspond with predetermined intervals of distance traveled by the vehicle at corresponding control points along the track, and means partly on the vehicle and partly on the track and including said adjusting means in part for controlling the operation of said permissive speed means and causing it to change to lower speed conditions from its then existing initial maximum speed condition whenever dangerous traffic conditions exist ahead and for restoring said permissive speed means to such initial maximum speed condition when traffic conditions ahead become safe.
42. In a system for automatically controlling the brakes of railway vehicles dependent upon their speed and traffic conditions, car-carried apparatus comprising a movable permissive speed device biased to a low speed position, gearing connected to the running gear of the vehicle for at times driving said device in opposition to its bias to higher speed positions, means for holding said device in its higher speed position to which it has been driven, together with means partly on the vehicle and partly on the track for independently controlling said driving means and said holding means.
43. In an automatic system of train control, changeable permissive speed means adapted to determine the limiting speed at which the vehicle may travel without an automatic application of its brakes, said permissive speed means having an inherent tendency to assume a low speed condition, means controllable to cause said permissive speed means to change, in opposition to its

tendency, to higher speed positions in accordance with distance traveled by the vehicle at predetermined points along the track, means for maintaining said permissive speed means in its adjusted higher speed condition; separate control devices on the vehicle for independently governing the driving means and the holding means; and means controlled from the trackway for independently controlling said control devices.

44. In a system for automatically controlling the brakes of railway vehicles if predetermined safe speed limits are exceeded, automatic brake control apparatus on the vehicle including a changeable permissive speed device determining the limiting speed which the vehicle can not exceed without an automatic brake application, means partly on the vehicle and partly on the track for actuating said permissive speed device from its existing initial maximum speed condition to other lower speed conditions during the progress of a vehicle through a space interval next in the rear of another train ahead, and automatic means acting irrespective of the presence or absence of another train ahead to adjust the initial maximum speed condition of said device in conformity with predetermined intervals of distance traveled by the vehicle at corresponding control points along the track where such adjustment is desired.

45. In a system of train control, the combination with brake control apparatus on a railway vehicle including a changeable permissive speed device determining the limiting speed which the vehicle can not exceed without an automatic brake application, of trackway influence communicating means permanently effective at selected control points along the track, and means on the vehicle cooperating with said trackway means to cause change of said permissive speed device to higher or to lower speed conditions to conform with predetermined intervals of distance at said control points.

46. A system of train control comprising, brake control apparatus on a railway vehicle including a movable permissive speed device biased to a predetermined position, and acting automatically in its various positions to determine different speed limits which the vehicles can not exceed without an automatic brake application, means on the vehicle operable to connect said device to the wheels of the vehicle and move it from its certain predetermined position to an extent corresponding with the distance traveled by the vehicle while said means is effective, and trackway means at selected control points along the track for rendering said means effective for a predetermined interval of distance at each of said control points irrespective of traffic conditions.

47. In a system of the character de-

scribed, apparatus for determining variable limited speeds for a railway vehicle which it can not exceed without an automatic brake application comprising, a movable permissive speed device biased to one position, a separately movable element biased to a certain initial position and operable to move said permissive speed device to different positions in opposition to its bias, means controlled from the trackway for driving said movable element from its initial position to an extent corresponding to the number of revolutions of the car wheels occurring while said means is effective, said movable element automatically returning to its initial position after each driving operation thereof, and other means controlled from the trackway for holding the permissive speed device in the position in which it may have been placed by said movable element.

48. In a train control system, apparatus for automatically determining safe limiting speeds for railway vehicles comprising, a movable permissive speed device, an operating element therefor, means controlled from the trackway for at times connecting said operating element to the wheels of the vehicle, said permissive speed device being shifted to a position corresponding to that to which said operating element is driven by the rotation of the wheels, and means controlled from the trackway in accordance with traffic conditions for maintaining said permissive speed device in its various adjusted positions independently of the position of said operating element.

49. In a train control system, apparatus for automatically determining safe limiting speeds for railway vehicles comprising, a movable permissive speed device biased to move in one direction, an operating element for said device biased to a predetermined initial position and adapted to drive the permissive speed device to various positions, means for coupling said operating element to the wheels of the vehicle for predetermined distances of travel at selected control points along the track, said element automatically returning to its initial position after each actuation thereof, and traffic controlled means partly on the vehicle and partly on the track for maintaining said permissive speed device in the different positions to which it is driven by said element.

50. In a train control system of the character described, the combination with a centrifugal speed responsive device on a vehicle driven from the wheels thereof, a changeable permissive speed means cooperating with said speed responsive device to automatically apply the brakes if the vehicle exceeds a speed corresponding to the existing condition of the permissive speed means, and automatic means for adjusting said per-

missive speed means to different positions and maintaining it in such adjusted position at selected control points along the track to conform with a predetermined interval of distance at each control point.

51. Speed control apparatus for railway vehicles of the character described comprising, a movable permissive speed device biased to move in one direction toward a low speed position, gearing coupled to the wheels of the vehicle and controllable to drive said permissive speed device in opposition to its bias to higher speed positions, an electrically operated mechanical detent device for holding said permissive speed device in its various positions, and means controlled from the trackway for automatically governing the operation of said detent device.
- 10 52. In a train control system, the combination with car-carried brake control apparatus including changeable permissive speed means and adapted to automatically apply the brakes of the vehicle whenever it exceeds a speed limit corresponding to the existing condition of said permissive speed means, means partly on the vehicle and partly on the track and automatically controlled in accordance with traffic conditions for regulating the change of said permissive speed means, and other means governed by a distinctive controlling influence from the trackway for independently regulating the condition of said permissive speed means to conform with predetermined intervals of distance traveled by the vehicle at selected control points along the track.
- 15 53. A system of train control for railway vehicles capable of enforcing predetermined variable speed limits, each when once established continuing during the progress of the vehicle until changed and characterized by the adjustment of the maximum speed limit

at selected control points along the track in conformity with intervals of distance traveled by the vehicle at such control points. 45

54. In a system of train control, changeable means on a vehicle for determining the limiting speed therefor, traffic controlled means for governing said changeable means, and means governed by a distinctive influence from the trackway for adjusting said changeable means at selected control points along the track to conform with a predetermined interval of distance at each control point. 50

55. In a train control system, the combination with car-carrier brake control apparatus including a changeable means adapted to prescribe any one of a plurality of different speed limits for the car, means operable to connect said changeable means to the wheels of the vehicle to vary the speed limit prescribed thereby, and trackway means co-operating with car-carried means for rendering said last mentioned means active for a predetermined interval of distance along the track. 60

56. In a train control system, the combination with brake control apparatus on a railway vehicle including a changeable permissive speed device, trackway means for communicating at least two distinctive influences to the vehicle, control means on the vehicle responding differently to said influences and controlling the change of said permissive speed device accordingly, and means effective at selected control points along the track for communicating another distinctive influence to the vehicle and varying the initial condition of said permissive speed device in conformity with varying intervals of distance traveled by the vehicle at said control points. 70
